[57] CLAIM

The ornamental design for a caddy for notions, as shown and described.

DESCRIPTION

FIG. 1 is a perspective view of a caddy for notions embodying my new design.

FIG. 2 is a top plan view.

FIG. 3 is a front elevational view;

FIG. 4 is a left side elevational view;

FIG. 5 is a right side elevational view; and

FIG. 6 is a bottom plan view thereof.

The partial showing of mesh at the bottom of the large compartment in FIGS. 1 and 2 is understood to be continuous within the boundaries shown.
